UNITED STATES PATENT OFFICE,

ROBERT BURNSIDE PATTERSON, OF LUDINGTON, MICHIGAN.

POTATO-DIGGER.

SPECIFICATION forming part of Letters Patent No. 617,992, dated January 17, 1899.

Application filed February 28, 1898. Serial No. 671,743. (No model.)

To all whom it may concern:

Be it known that I, ROBERT BURNSIDE PATTERSON, of Ludington, in the county of Mason and State of Michigan, have invented a new 5 and useful Improvement in Potato-Diggers, of which the following is a full, clear, and exact description.

The object of my invention is to provide a potato-digger which will not only dig the potatoes, but sort them and deliver them to 10 crates or other receptacles provided to receive them.

A further object of the invention is to construct a potato-digger which will operate satisfactorily in any character of good potato soil and which will operate in a manner to do the least possible damage to the potatoes being dug, but which will be simple, durable, and economic and have but few wearing-surfaces exposed to drifting sands and wherein no gearing or shakers common to most machines of this character and liable to great wear and friction are employed.

A further object of the invention is to so construct the machine that the driver may be seated at the rear and will have perfect control of the machine, being able to raise or lower the digging-fork whenever necessary.

The invention consists in the novel construction and combination of the several parts, as will be hereinafter fully set forth, and pointed out in the claims.

Reference is to be had to the accompanying drawings, forming a part of this specification, 35 in which similar characters of reference indicate corresponding parts in all the figures.

Figure 1 is a side elevation of the machine. Fig. 2 is a vertical longitudinal section on the line 2 2 of Fig. 3. Fig. 3 is a plan view of 40 the machine. Fig. 4 is a section through the front portion of the frame, showing the main portion of the machine in front elevation. Fig. 5 is a section through the axle close to one of the supporting-wheels and a section 45 through one of the receptacles for potatoes, illustrating the major portion of the machine in side elevation and the application thereto of a conveyer; and Fig. 6 is a plan view of that portion of the machine at which the conveyer is located.

A represents the frame of the machine, which may be of any desired character and

preferably consists of two side bars connected at the rear and at the front of the machine. A platform 10 is constructed on or suspended 55 from the frame at the front and a second platform 11 is laid at the rear, the driver's seat 12 being at the rear of the machine, so that all operative parts of the machine are within the vision of the driver. The frame 60 is provided with attached bearings 13, whereby it is suspended from an axle 14, and the said axle has a supporting-wheel 14^a attached to each of its ends outside of the said frame, as shown best in Figs. 3 and 4. 65

At or near the central portion of the side bars of the frame hangers 15 are projected downward to a point near the ground, the said hangers being adapted to sustain journals of a rock-shaft 16, a crank-arm 17 whereof 70 is preferably centrally located and is also preferably somewhat rectangular in cross-section. Rods 18 are passed through the crank-arm 17, being held removably and adjustably in engagement with said shaft by set-screws 75 19 or their equivalents. The said rods 18, which are preferably sharpened at their forward ends, in connection with the crank-arm 17, constitute the digging-fork of the machine when the machine is used in loose and sandy 80 soil. When, however, the soil is of a different character, a frame is used in connection with the rods or tines 18, the said frame consisting of a beveled lower horizontal member 20 and upwardly and preferably outwardly 85 flaring side members 21, the said side members being provided at their rear ends with sleeves 22, receiving the outermost tines 18^a of the fork, which outermost tines 18^a are preferably rectangular in cross-section, as shown 90 in Fig. 1, set-screws 23 being employed to secure the frame to the said outer tines 18^a, and the lower ends of the tines of the fork, when the frame is employed, are made to enter openings 24, made in the lower or digging section 95 of the frame, as illustrated in Fig. 2. A lever 25 is attached to the rock-shaft 16, preferably at the right-hand end of the machine, the said lever extending upward within convenient reach of the driver, and through the medium 100 of the said lever 25 the shaft 16 may be rocked to raise the lower end of the digging-fork as occasion may demand.

An assorting-cylinder B is mounted upon

the axle 14 and turns with the said axle. The assorting-cylinder consists of a ring 26, forming one end and located at the left-hand end of the machine, and a disk 27, constituting the other end and located at the right-hand side of the machine, the disk 27 being secured by set-screws and an attached sleeve 28 to the shaft 14, or the attachment may be made in any other suitable manner. The two parts 26 and 27, which constitute the heads of the assorting-cylinders, are connected by cross-bars 29, placed at suitable intervals apart, as shown in Fig. 2. Preferably the ring 26, the disk 27, the sleeve 28, and the cross-bars 29 are all one casting.

A series of fingers 30 is secured to each of the cross-bars 29. These fingers may be of the same length or may be graduated in length from the center in direction of the ends, as shown in Fig. 4, the end fingers being more curved than the center fingers. All of the fingers are curved, and the curvature is such that when the fingers are at the rear of the cylinder they extend upward and rearward, each series of fingers forming a long pocket for the reception of potatoes. Bands 31 are located between the heads of the assorting-cylinder, the bands passing between the fingers 30 on the said cross-bars 29. By this construction the cylinder is provided with openings through which small potatoes may fall, and these small potatoes are received by a slotted chute 32. The head or higher end of the chute 32 is carried near to the closed head 27 of the cylinder, as shown in Figs. 2 and 4, and is suspended at said raised end from the shaft 14 by means of a strap 33. The chute extends out through the open end of the cylinder, and the chute at its lower end is provided with arms 34, which are bolted or otherwise secured to the frame. The potatoes received by the chute 32 are delivered into a receptacle 35, supported by the frame at its left-hand side, the said receptacle being preferably given a downward inclination at its front portion, and the receptacle is provided at its rear end preferably with a gate capable of being operated by the driver in order that the potatoes may be delivered from said receptacle when desired. This gate being of ordinary construction has not been illustrated.

A guard C is formed at the rear of the machine. This guard consists of a series of downwardly and forwardly curved bars 36, their concaved faces being toward the front. The upper ends of these guard-fingers are bolted or otherwise secured to a concaved surface 37 of a cross-bar 38, extending from side to side of the machine-frame at the rear of the assorting-cylinder, or the said guard bars or fingers may be attached directly to the platform 11. The distance between the guard fingers or bars and the assorting-cylinder and the relation of the said bars or fingers to the assorting-cylinder are such that the guard fingers or bars will not interfere with

the upward movement of the carrying-fingers 30 on the assorting-cylinder, but the carrying-fingers on the assorting-cylinder will pass 70 so close to the guard-fingers 36 as to prevent any potatoes escaping between the two sets of fingers.

The end carrying-fingers 30 may be and preferably are of less length than the central carrying-fingers, and the guard C is correspondingly curved. The guard-rods 36 at their lower ends are preferably connected by a bar 39, as shown in Fig. 2, and the guard is held in proper relation to the digging-fork by 80 means of hooks 40 or their equivalents, which are connected at the end of the connecting-bar 39 of the guard and are carried over the rock-shaft 16.

In the operation of the machine as it is 85 drawn forward the digging-fork will turn up the potatoes from the soil. The potatoes will be carried rearward over the tines of the fork and will be taken up by the carrying-fingers 30 of the assorting-cylinder as said cylinder 90 revolves. The carrying-fingers will carry both the large and the small potatoes upward, assisted by the guard C, the pocket formed by the set of carrying-fingers serving to hold the potatoes after the said set of fingers has passed 95 from the guard C. When the carrying-fingers of a set have reached a point at the upper portion of the cylinder, the potatoes carried thereby will be spilled upon the cylinder and the small potatoes, as stated, will drop through 100 the openings in the cylinder to the chute 32, where the earth will escape and the small potatoes be conveyed to the receptacle 35, while the larger potatoes will slide down the bands at the front of the assorting-cylinder and 105 strike the concaved faces of the next set of carrying-fingers below their point of discharge and will be directed by these fingers into the crate 41, a basket, or other receptacle placed upon the front platform 10 in position 110 to receive them.

It is evident that the machine is exceedingly simple, durable, and economic, that it is within the entire control of the driver, and that each and every part of the machine is 115 conveniently within the range of vision of said driver; furthermore, that the fork for digging the potatoes may be regulated as the character of the soil may demand by being moved forward on the frame and having extra sets of guard-rods 36 to reach the rock-shaft.

Instead of conveying the smaller potatoes directly to the receptacle 35 at the rear bottom portion of the frame of the machine the potatoes may be and preferably are conveyed to a removable receptacle 42, which is supported upon the frame of the machine at the rear, adjacent to the driver's seat. When the form of receptacle 42 is employed, the open end of the assorting-cylinder B is provided 120 with an attached sprocket-wheel 43, or teeth are formed thereon to produce a sprocket-wheel, while a sprocket-pinion 44 is mounted to revolve on the side of the driver's seat or

on a support provided for it at the rear of the machine. The conveyer-chain 45 is passed over the sprocket-wheel 43 on the assorting-cylinder and over the sprocket-pinion 44, the said conveyer-chain being provided with transverse plates 46 on its outer face. The small potatoes are delivered by the slotted chute 32 into a pocket 47, located at the delivery end of said chute and carried by the frame of the machine, as shown in Figs. 5 and 6. This pocket is provided with an extension in the shape of a chute 48, which is carried upwardly and rearwardly into the receptacle 42. The conveyer-chain 45 passes through the pocket 47, the bottom whereof is cylindrical, and through the chute 48 or extension of the pocket. Therefore the small potatoes are carried up in the chute 48 by the plates of the conveyer-belt and dropped into the receptacle 42.

Having thus described my invention, I claim as new and desire to secure by Letters Patent—

1. In a potato-digger, an assorting-cylinder mounted to revolve and provided with peripheral pockets adapted to receive potatoes, and with peripheral openings through which small potatoes may pass to the interior of the assorting-cylinder, and a receptacle to which the potatoes that pass through the peripheral openings in the cylinder are conducted, for the purpose specified.

2. In a potato-digger, an assorting-cylinder provided with peripheral pockets adapted to receive and take up potatoes, and with peripheral openings through which small potatoes may pass, and a chute located within the said cylinder, adapted to receive the potatoes that drop through the peripheral openings in the cylinder, for the purpose set forth.

3. In a potato-digger, an assorting-cylinder, said cylinder being provided with a closed and with an open head, the said cylinder being further provided with peripheral openings and series of curved fingers arranged to form transverse pockets, the fingers being located opposite the openings in the periphery of the cylinder, and means for rotating the said cylinder, as and for the purpose specified.

4. In a potato-digger, an assorting-cylinder, said cylinder being provided with a closed and with an open head, the said cylinder being further provided with peripheral openings and series of curved fingers arranged to form transverse pockets, the fingers being located opposite the openings in the periphery of the cylinder, means for rotating said cylinder, and a fixed inclined chute suspended within the said cylinder, the lower end of the said chute extending beyond the open head of the cylinder, for the purpose specified.

5. In a potato-digger, the combination, with a shaft provided with a crank-arm, and means for rocking the shaft, of a digging-fork consisting of tines secured in the crank-arm of the rock-shaft, and a frame comprising a lower digging member and side members, the said

frame being removably attached to the said fork, the lower ends of the tines of the fork entering the digging member of the said frame, for the purpose specified.

6. In a potato-digger, the combination, with an assorting-cylinder mounted to revolve, the said cylinder having peripheral pockets extending outward from the periphery of the cylinder and peripheral openings through which small potatoes may pass to the interior of the cylinder, and a receptacle to which the potatoes that pass through the peripheral openings are conducted, of a digging-fork located at the front of the lower portion of said cylinder, and an apertured guard located at the rear of the bottom portion of said cylinder, and in communication with the said fork, for the purpose specified.

7. In a potato-digger, the combination, with an axle, supporting-wheels secured to the said axle, a frame suspended from the axle, a rock-shaft carried by the frame, and a digging-fork carried by the said rock-shaft, of an assorting-cylinder attached to the said axle, comprising a closed and an open head, cross-bars connecting the said heads, curved carrying-fingers arranged in transverse series, attached to the said cross-bars, and bands carried by the cross-bars and passed between the carrying-fingers, as and for the purpose specified.

8. In a potato-digger, the combination, with an axle, supporting-wheels secured to the said axle, a frame supported from the axle, a rock-shaft carried by the frame, and a digging-fork carried by the said rock-shaft, of an assorting-cylinder attached to the said axle, comprising a closed and an open head, cross-bars connecting the said heads, curved carrying-fingers arranged in transverse series and attached to the said cross-bars, and bands carried by the cross-bars and passed between the carrying-fingers, a slotted chute secured to the said frame, extending in an inclined position through the open end of the cylinder from its closed end, and a guard at the rear of the said cylinder, the said guard extending to the rear portion of the said digging-fork, substantially as and for the purpose specified.

9. In a potato-digger, the combination, with an axle, supporting-wheels secured to the said axle, a frame supported from the axle, a rock-shaft carried by the frame, and a digging-fork carried by the said rock-shaft, of an assorting-cylinder attached to the said axle, comprising an open and a closed head, cross-bars connecting said heads, curved carrying-fingers arranged in transverse series and attached to the cross-bars, and bands carried by the cross-bars and passed between the carrying-fingers, a slotted chute secured to the said frame, extending in an inclined position through the open end of the cylinder from its closed end, a guard at the rear of said cylinder, a receptacle located at the front and a receptacle at the rear of the cylinder, a pocket formed at the delivery end of the said chute,

provided with a trough extending into the rear receptacle, a conveyer-chain driven by the cylinder and arranged to pass through the said pocket and the said trough, and means 5 for supporting the said conveyer-chain, substantially as described.

10. In a potato-digger, the combination with a wheel-supported frame, of a digging-fork, an assorting - cylinder mounted to revolve 10 and provided with peripheral fingers forming pockets adapted to receive potatoes, a receptacle carried by the frame and into which the larger potatoes are delivered, the said assort-

ing-cylinder being provided with peripheral openings through which small potatoes may 15 pass to the interior of the cylinder, a chute located within the assorting - cylinder, and adapted to receive the potatoes that drop through the peripheral openings in the cylinder, and a receptacle to which the small potatoes are conveyed, substantially as described. 20
